[57] **CLAIM**

The ornamental design for a foldable measuring apparatus, as shown and described.

DESCRIPTION

FIG. 1 is a front perspective view of the foldable measuring apparatus showing my new design in a storage position; FIG. 2 is a front perspective view of the foldable measuring apparatus showing my new design in an extended position; FIG. 3 is a front plan view of the foldable measuring apparatus showing a display panel having readable indicia; FIG. 4 is a rear plan view of the foldable measuring apparatus;

FIG. 5 is a side plan view of the foldable measuring apparatus showing the storage position;

FIG. 6 is a side plan view of the side opposite that shown in FIG. 5 of the foldable measuring apparatus;

FIG. 7 is a bottom plan view of the foldable measuring apparatus; and,

FIG. 8 is a top plan view of the foldable measuring apparatus.

The broken line showing is for illustrative purposes only and forms no part of the claimed design.
